A. & S. DE PAEMELAERE.
KEY GUARD.
APPLICATION FILED JULY 14, 1908.

902,948.

Patented Nov. 3, 1908.

UNITED STATES PATENT OFFICE.

ARTHUR DE PAEMELAERE AND SYLVIN DE PAEMELAERE, OF GARDENA, CALIFORNIA.

KEY-GUARD.

No. 902,948

Specification of Letters Patent. Patented Nov. 3, 1908.

Application filed July 14, 1908. Serial No. 443,547.

To all whom it may concern:

Be it known that we, ARTHUR DE PAEMELAERE and SYLVIN DE PAEMELAERE, both citizens of the United States, residing at Gardena, in the county of Los Angeles and State of California, have invented a new and useful Key-Guard, of which the following is a specification.

This invention relates to a device which is adapted to be applied, on the inside of the door, to the key and engaged with the lock to prevent the key from being turned from the outside, it being so constructed that the key cannot be turned from the outside by employing pincers, wires, or any other tools from the burglar's kit.

Another object of the invention is to so construct the device that it may be readily attached to or detached from the key and may be easily folded into compact form convenient for carrying in the pocket. The device is of especial advantage for traveling men or household use.

A further object of the invention is to so construct the device that it may be readily adjusted to fit any size of key.

Referring to the drawings Figure 1 is a perspective view of a portion of the inside of the door and lock showing the key inserted in the lock and the key turned to locking position with the guard applied in operative position to prevent the key being turned. Fig. 2 is a plan view of the guard with the hinged plate removed. Fig. 3 is a cross section on line x^3-x^3 Fig. 2. Fig. 4 is a perspective of the guard when folded for carrying in the pocket. Fig. 5 is a sectional plan view of the adjusting plate.

The guard comprises a rectangular guide plate 1 having its edges down turned and bent inwardly to form guides 2. Arranged below the guide plate 1 and slidably mounted in the guides 2 is an adjusting plate 3 having a longitudinal slot 4 through which a rivet 5 projects there being a washer 6 at the lower end of the rivet 5 serving to aid in retaining the adjusting plate and the rivet also acting as a stop to limit the extreme sliding movement of the adjusting plate. A guard plate 7 is hinged at 8 to the upturned end of the adjusting plate 3 and has its free end curved upwardly at 9 enabling it to be easily grasped by the fingers to swing it upwardly when desired. A stud 10 is secured to the guard plate 7 and acts as a leg or stop which

when the guard plate is folded down, rests against the guide plate 1 and spaces the guard plate 7 from the guide plate 1 leaving a recess adapted to receive the key as will be described, the stud 10 being of a length which holds the guard plate 7 substantially parallel with the guide plate 1. A locking stud 11 is also secured to the guard plate 7 and has a shoulder 12 adapted to rest against the guide plate 1 while its locking portion 13 is adapted to project through any one of a series of holes 14 formed in the guide plate 1, the adjusting plate 3 having a single hole 15 through which the locking portion 13 also projects so that when the guard plate 7 is folded parallel with the guide plate 1 the locking portion of the stud 11 positively locks the adjusting plate 3 against sliding movement in the guide plate 1. In order to prevent the guard plate 7 from being swung up to withdraw the locking stud 11 except when desired a clasp 16 is provided which is pivoted at 17 at one edge of the guard plate 7 and has a hook-shaped portion 18, the latter having a hole 19 which is adapted to spring over the lower end of the locking portion 13 and thus when in this position the hook 18 is prevented from swinging out by the locking portion 13 of the stud 11, while the hook 18 in turn prevents the guard plate 7 from being swung up.

A locking dog 20 is carried on a pintle 21 journaled at 22 on the guide plate 1 and the locking dog 20 may be folded to lie between the guide plate 1 and guard plate 7 as shown in Fig. 4 for carrying in the pocket, or it may be extended as shown in Figs. 1 and 2 to project through the key hole 23 into the lock 24 as shown in Fig. 1 to prevent the key from turning when the device is applied. The locking dog has a projection 25 which is adapted to rest against the lower face of the guide plate 1 to prevent the locking dog from being turned too far over and to hold it in line with the guide plate 1 when it is extended.

26 designates the key which in Fig. 1 is shown as having been turned in the lock to lock the door, and when the key is in this position the device may be applied to the key by first opening guard plate 7, then swinging out the locking dog 20 to extend straight from the guide plate 1, then slipping the locking dog 20 through the key hole under the key and bringing the guide plate 1 up close

under the key, then swinging down the guard plate 7 so that the studs 10 and 11 lie on opposite sides of the key 26, then swinging the clasp 18 into locking position to hold the guard plate closed. When the guards are in this position it will be observed that the key 26 is securely fastened to the device and cannot be turned with respect to the device as the flat bow 27 of the key lies between the guard plate 7 and guide plate 1, while the guard itself is prevented from turning by reason of the locking dog 20 which fits sufficiently close in the key hole and lock. It should be noted that if it is attempted to push the guard device off from the key by inserting a wire from the outside of the lock that the studs 10 and 11 will strike the bow 27 of the key and thus prevent the guard from being moved further inward and the key of course cannot move inward as it is already turned in the lock to locking position.

The device may readily be detached from the key and folded to be carried in the pocket by first releasing clasp 18, then swinging up guard plate 7 which allows the device to be withdrawn and then the guards may be folded into the position shown in Fig. 4. The adjusting plate 3 may be shifted longitudinally on the guide plate 1 to accommodate different lengths of keys, the several holes 14 enabling the locking stud 11 to be inserted when the adjusting plate 3 is in various positions so that the latter is always locked positively against sliding motion when the guard plate 7 is closed.

What we claim is:

1. A key guard comprising a guide plate, an adjusting plate slidable thereon, a guard plate hinged to the adjusting plate, and a locking dog on the guide plate adapted to project through the key hole of the lock, the

guard plate and guide plate being adapted to receive the protruding portion of the key.

2. A key guard comprising a guide plate having its edges bent to form guides, an adjusting plate slidable in said guides, a guard plate hinged to the adjusting plate, means for detachably locking the guard plate in a position substantially parallel to the guide plate, and a locking dog on the guide plate. 45

3. A key guard comprising a guide plate having its edges bent to form guides, an adjusting plate slidable in said guides, a guard plate hinged to the adjusting plate, means for detachably locking the guard plate in a position substantially parallel to the guide plate, and a locking dog on the guide plate and hinged thereto whereby it is adapted to be extended to project into the key hole or to be folded between the guide plate and guard plate. 55

4. A key guard comprising a guide plate having a series of holes, an adjusting plate slidable on the guide plate and having a hole, a guard plate hinged to the adjusting plate, a stud on the guard plate adapted to rest against the guide plate, a locking stud on the guide plate adapted to project through a hole in the guide plate and the hole in the adjusting plate, a clasp hinged to the guard plate 65 and adapted to engage the guide plate and locking stud, and a locking dog hinged to the guide plate and adapted to project into the key hole. 70

In testimony whereof, we have hereunto set our hands at Los Angeles, California, this 75 seventh day of July, 1908.

ARTHUR DE PAEMELAERE.

SYLVIN DE PAEMELAERE.
